UNITED STATES PATENT OFFICE.

ORVIS W. VALLIER, OF WATERTOWN, NEW YORK, ASSIGNOR TO J. B. WISE INCORPORATED, OF WATERTOWN, NEW YORK, A CORPORATION OF NEW YORK.

SHUT-OFF FOR SINK FAUCETS.

Application filed July 12, 1926. Serial No. 121,945.

This invention relates to sink faucets and has especial reference to faucets comprising mixing valves operable by single handles.

The primary object of the invention is to provide a novel form of individual shut-off mechanism for each supply arm of the faucet, whereby the water may be entirely shut-off, while the mixing valve or other parts of the faucet are being repaired, thereby obviating the necessity of the repairer making trips to other parts of a building in order to operate the usual shut-off valves. A further object is to provide the cold and hot water arms of the faucet with separate shut-off means, whereby the flow of the water from said arms may be suitably proportioned or equalized, in cases where the pressure of the cold and hot water is normally unequal, the shut-off mechanism consisting of similar valves or gages, which are located in the cold and hot water arms of the fitting, and are arranged to be adjusted and set at will, for stopping, equalizing, or varying the volume of the water supply to the opposite sides of the dispensing valve without interference with the normal operation of the faucet.

I attain these objects by the means set forth in the detailed description which follows, and as illustrated by the accompanying drawing, in which—

Figure 1 is a top plan view of a sink or bath faucet to which my improvement is applied. Fig. 2 is a front side elevation and partial central vertical section, the latter being taken on line 2—2 of Fig. 1; showing the individual shut-off mechanisms in relation to the mixing valve. Fig. 3 is an enlarged side view of one of the shut-off valves. Fig. 4 is respectively an end and a side elevation of one of the bushings that support the shut-off valves.

In the drawing, 2 designates the upright wall of a sink or bath tub, which usually supports the water dispensing fittings. 3 represents the upright cylindrical body of one type of the mixing valve, which is formed with a tapered seat 3', to receive the rotary valve 4, the latter being operable by a stem, whose top end is fitted with a handle 2''. The valve 4 is arranged to dispense water at different temperatures by the simple manipulation of the handle 2'', as shown by the

full and dotted lines in Figs. 1 and 2, wherein the full lines in Fig. 1 indicate that the valve 4 is positioned for dispensing cold water, while the full lines in Fig. 2 indicate the positioning of the valve for dispensing warm water, which may comprise substantially equal volumes of hot and cold water. The dotted positions at the right in Figs. 1 and 2 indicate the drawing of hot water only.

In Figs. 1 and 2, the body 3 is shown formed at its opposite sides with similar axially aligning circular recesses or sockets 3^a—3^b, which are preferably threaded for the attachment of similar hollow water supply arms, as 5—5', whose corresponding ends are externally threaded for screwing into said sockets. These joints are usually soldered for preventing leakage. The remote ends of the arms 5—5' are preferably globular, and are formed with integral tubular arms 5^a, which together with nipples 5^b form the usual tail-pieces that extend rearwardly, pass through the wall 2, and connect respectively with the cold and hot water supply-pipes (not shown). The arms 5—5' conduct the cold and hot water respectively to the sockets 3^a—3^b, from which the water flows through reduced aligning ducts 3^c towards the valve chamber 3', and when the valve 4 is in the position shown in Fig. 2, the cold and hot water flow simultaneously through registering ports 4^b—4^c, and thence into a common mixing chamber 4^d, from which the mixture gravitates towards a common spout A, which may be either rigid or swingable. The passages 3^c, at their outer extremities, are preferably countersunk, as at 3^d.

The shut-off means consist of similar horizontally disposed valves, which may comprise plain brass or other rods, as 6—6', that are preferably disposed axially in the arms 5—5', their inner ends 6^a, being beveled, and adapted to be seated in the mouths 3^d of the passages 3^c, for shutting off entirely the supply of water to the valve 4. The outer ends of the valves 6—6', are correspondingly threaded, as at 6^b, and are also provided with screw-driver slots 6^c, by which the said valves are rendered adjustable axially in internally threaded bushings 7. The bushings 7 are also externally threaded and are screwed into threaded sockets 5^d of the arms

5—5'. The bushings 7, according to the present showing, are the sole supports for the shut-off valves 6—6'. The sockets 5^a are formed in correspondingly thickened portion 5^c, which may be cast in the globular extremities of the arms 5—5'. By comparing the relative positions of the valves 6—6' in Fig. 2, it will be seen that the valve 6 is disposed closer to its seat 8^a, than the valve 6', which indicates that because the cold water is being supplied at higher pressure than is the hot water, the opening controlled by the valve 6 must be more constricted than is that controlled by the valve 6' in order to allow equal volumes of hot and cold water to flow towards the mixing valve 4. By this construction and arrangement of the valves 6 and 6' and the main valve 4, either the hot or the cold water supply may be readily and quickly regulated, and a relatively fine adjustment of the parts may be effected, by simply adjusting the valves 6—6' axially, as shown and described, and when these valves are once adjusted they need not be disturbed, until the pressure of either the hot or the cold water supply is increased or decreased. The bushings 7 are preferably counterbored, as at 7', for facilitating applying a suitable packing 8, which prevents leakage through the sockets 5^a. Because of the provision of the screw-driver slots 6^e instead of handles, for adjusting the shut-off valves 6—6', the adjustment of the said valves is not liable to be disturbed either accidentally or by tampering.

Obviously my shut-off valves may be applied to other types of faucets or valves, and the construction and arrangement of the parts may be changed or varied within the scope defined by the appended claims without departing from my invention.

Having thus described my invention, what I claim, is—

1. In a faucet, a body having hollow opposed hot and cold water supply arms, a mixing valve in the body, said arms having globular outer ends formed with inwardly projecting thickened sockets which latter are interiorly threaded, valve rods in the arms to control the entry of water into the body and having exteriorly threaded outer ends, bushings having interior threads engaged with the valve rod threads and having exterior threads engaged with the socket threads so as to constitute supports for the rods, the inner ends of the bushings being counterbored, and packing in the counterbored parts of the bushings the outer ends of the valve rods having screw-driver receiving slots. 45 50 55 60

2. In a faucet, a body having hollow opposed hot and cold water supply arms, a mixing valve in the body, said arms having globular outer ends formed with interiorly threaded and inwardly projecting sockets 65 having perforated bottoms, valve rods in the arms extending through the perforations of the bottoms of the sockets to control the entry of water into the body and having exteriorly threaded outer ends, bushings in the 70 75 80 85 90 95 sockets having interior threads engaged with the valve rod threads so as to constitute supports for the rods, and having exterior threads engaged with the socket threads, packing between the socket bottoms and the inner ends of the bushings, and means to effect rotation of the valve rods within the bushings.

In testimony whereof I affix my signature.

ORVIS W. VALLIER.
